Claims priority, application France Apr. 21, 1960
2 Claims. (Cl. 277—141)

The object of the invention is to provide a composite piston ring which not only ensures fluid-tightness but also cleans the sliding-surfaces of the cylinder and evacuates the films removed from the surfaces.

It is characterised by the means used, considered both in conjunction with one another and independently of one another, and more particularly by a ring with an oblique vertical face set back between an upper and a lower shoulder, constituting a peripheral groove. On each side of this ring are disposed thin scraper elements which project to a small distance, in such a way as to provide with the ring three scrapers for contact on the cylinder. The oblique vertical face thus forms a central external 20 peripheral groove.

On the attached drawings, illustrating by way of an example, and without any limitative effect, one possible constructional version of the invention:

FIGS. 1 and 2 are a plan view and a side view of the ring proper;

FIG. 3 is a cross section through the same device;

FIGS. 4 and 5 illustrate the elastic scraper members;

FIG. 6 is a schematic cross section of the elements of which the ring consists.

The ring in FIGS. 1 and 2 consists of a metal hoop on the lower and upper faces of which are vertically rigid overlapping protuberances 18 and 19, with recesses 18¹ and 19¹, these protuberances being set back horizontally in order to provide the spaces 20, 21.

The vertical wall is rectilinear on the inside, as shown at 22, and oblique on the outside, as shown at 23.

The elastic scraper members 24 and 25, in FIG. 6, are situated on the shoulders, and their external edges 26 and 27 project by the same distance as the point 23 of the oblique side, so that they are situated in the projection of the axis XY, representing the wall of the cylinder.

A mounting 28, which functions as a spring, is polygonal in section and has cut-out parts 29 and 30 to ensure elasticity, comes to bear against the internal vertical face 22, and forces it outwards to enable it to fit tightly against the cylinder.

The ring proper only has one scraper-edge 23. This edge is situated between the other two elastic scraper members 26 and 27, which are spaced out and which act on the lower and upper faces.

2

These three "sliding joints" increase the hermeticity of the ring, and the "grooves" 20 and 21, with their orifices 18¹ and 19¹, enable the waste matter to be removed and collected.

5 The elastic packing 28 adds to the thrust of the ring that of its recesses 29 and 30, in addition to its own bending, so that this triple elasticity absorbs the expansion and contraction-effects and thus assists in ensuring the complete fluid-tightness of the ring, whether cold or hot. 10 Finally, the scraper edges situated on different planes and mutually independent, although constituting a homogeneous unit, without any discontinuity, ensure maximum strength combined with maximum efficiency.

The forms, dimensions and arrangements of the various elements may nevertheless vary within the limits allowed by equivalent devices, as may also the materials used for their manufacture, without thereby departing from the general principle of the invention described in the foregoing.

I claim:

1. A composite cylinder and piston ring assembly comprising a cylinder wall, a first central ring provided with circumferential staggered upper and lower set back shoulders for the collection of oil and a vertically oblique face terminating in a scraper edge, a resilient member urging said central ring scraper edge outward against said cylinder wall, and second and third elastic scraper members disposed respectively above and below said shoulders in scraping engagement with said cylinder wall, whereby 25 three mutually independent scraper elements in vertical array successively engage the cylinder wall and are separated from each other by two oil grooves formed as shoulder recesses set back from the oblique face of said central ring.

30 2. An assembly as claimed in claim 1 in which the resilient member for urging the central ring outward comprises a split polygonal spring.
